Primary Examiner — Jonathan J Han

(74) Attorney, Agent, or Firm — HAUPTMAN HAM, LLP

(57) **CLAIM**

The ornamental design for a sandal as shown and described.

DESCRIPTION

FIG. 1 is a front view of a sandal in a right-footed form according to my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of the sandal in a left-footed form;

FIG. 8 is a rear view thereof;

FIG. 9 is a right side view thereof;

FIG. 10 is a left side view thereof;

FIG. 11 is a top view thereof; and,

FIG. 12 is a bottom view thereof.

The broken lines depict the sole of the sandal that forms no part of the claimed design.

1 Claim, 12 Drawing Sheets
